PAIR OF HAND HELD EYEGLASSES

Lillian Brown, Chicago, Ill.

Application October 12, 1953, Serial No. 27,131

Term of patent 14 years

(Cl. D57—1)

To all whom it may concern:

Be it known that I, Lillian Brown, a citizen of the United States, residing at Chicago, county of Cook, and State of Illinois, have invented a new, original, and ornamental Design for a Pair of Hand Held Eyeglasses, of which the following is a specification, reference being had to the accompanying drawing, forming a part hereof, in which—

I claim:

The ornamental design for a pair of hand held eyeglasses, as shown.
